SERVOMOTOR

Edward Dodson, Putney Heath, London, S. W. 15,
EnglandApplication September 26, 1940, Serial No. 358,415
In Great Britain January 3, 1940

2 Claims. (Cl. 137—139)

The invention provides a hydraulic servomotor which includes a device normally overridden by the pressure fluid but operative to move the piston to a definite predetermined position, should the pressure of the fluid be released with the piston in a position unfavourable to the working of the apparatus to be operated by the servomotor. The device for moving the piston to the predetermined position on release of the pressure fluid may conveniently be constituted by a spring.

The invention is of particular, but not exclusive, application to remote acting throttle controls for internal combustion engines, more particularly aero engines. Fluid pressure may be absent in the servomotor either by reason of a mechanical failure or because the engine which produces the pressure has not commenced to operate. When an aero engine is to be started up, there will be no pressure fluid to operate the servomotor unless a fluid pressure reservoir is provided, and unless the cowling is dismantled it is not possible to set the throttle valve at the starting position by hand. By employing the invention, however, it may be arranged that should the pressure fluid in the servomotor be released, with the throttle valve in the idling position, the piston of the servomotor will at once move the throttle valve into an open position suitable for starting.

One embodiment of the invention as applied to a remote acting throttle control for an aero engine will now be described in detail, by way of example, with reference to the accompanying drawings, in which

Figure 1 is an elevation of the servomotor, partly broken away, Figure 2 is a section taken on the line II—II in Figure 1,

Figure 3 is a diagram illustrating the connections between the pilot's throttle lever, the servomotor and the throttle valve,

Figure 4 is an elevation of the sender unit associated with the pilot's throttle lever,

Figure 5 is a section on the line V—V in Figure 4, and

Figure 6 is a section on the line VI—VI in Figure 5.

The servomotor consists of the usual cylinder 10, piston 11, piston valve 12, swinging lever 13, pivoted at 14 to a bracket 15 projecting from the housing of the motor and at 16 to a fitting 22 on the lower end of the piston rod 22, and follow-up gear 16. 17 is an oil inlet port and 18 is an oil outlet port. The motor is controlled by compressed air admitted through a port 19 and operative on the upper surface of a diaphragm 20 con-

nected to the piston valve 12. The action of the diaphragm 20 on the piston valve 12 is opposed by springs 21. The pressure of the compressed air operating on the upper surface of the diaphragm 20 is varied in accordance with the position of the pilot's throttle lever through the intermediary of a sender unit 23 illustrated in Figures 4—6. The sender unit 23 comprises a two-part casing containing a diaphragm 40 clamped between the two parts of the casing. The upper surface of the diaphragm 40 is exposed to atmospheric pressure and its lower surface is exposed to compressed air admitted to the lower portion 51 of the casing through an inlet 41 under the control of an inlet valve 42. An exhaust port 43 in the lower portion of the casing is controlled by an exhaust valve 44. The valves 42, 44, respectively, actuated by tappets 45, 46 are attached to a rocking yoke 47 pivotally mounted at 48 and pivoted at 49 to a lug 50 fixed to the diaphragm 40. Downward movement of the diaphragm therefore tends to rock the yoke 47 clockwise as seen in Figure 3 and so open the inlet valve 42, whilst upward movement of the diaphragm tends to open the exhaust valve 44. Thus the diaphragm tends to maintain a predetermined pressure in the lower portion 51 of the casing, determined by the loading of a spring 52 acting on the upper surface of the diaphragm. The upper end of the spring 52 rests against a plunger 53 on which is fixed a cap 54 mounted to slide vertically at the upper part of the sender unit, a cam 55 being provided for depressing the cap and thereby varying the loading of the spring 52. The cam 55 is carried on trunnions 56 extending through bearings 57 on the top of the sender unit, which trunnions are operated by an arm 58 connected to the pilot's throttle lever (not shown). The setting of the cam 55 and consequently the air pressure maintained in the chamber 51 therefore depend on the setting of the pilot's throttle lever. An outlet port 59 in the chamber communicates, by way of a pipe 60, with the inlet port 19 and diaphragm 20 of the servomotor. The setting of the diaphragm 20 will therefore also correspond to the setting of the pilot's throttle lever. On movement of the diaphragm 20, the piston valve 12 is displaced in the appropriate direction opening ports for connecting one side of the cylinder 10 to the oil inlet 17 and the other to the oil outlet 18. Thus, supposing the air pressure above the diaphragm 20 to decrease, the piston valve 12 will be displaced upwardly,

permitting oil to flow from the inlet 17 through ports 29, 30 to the top of the cylinder and from the bottom of the cylinder through ports 32, 33, 34 to the oil outlet 18. The piston 11 will therefore move down, swinging the lever 13 clockwise about its pivot 14 and lowering the piston valve 12 to its neutral position through the intermediary of the follow-up gear 16 in the well known manner. Conversely, if the pressure above the diaphragm 20 increases, the piston valve 12 will move down, connecting the oil inlet 17 through the ports 29, 33, 32 to the lower end of the cylinder, and the upper end of the cylinder through the ports 31, 30, 34 to a passage 35 connected to the oil outlet 18. The connection between the passage 35 and the outlet 18 is not shown in Figure 2 because it lies above the plane of the section. It is however constituted by a bore formed in the wall of the servomotor. The piston 11 will therefore rise, returning the piston valve 12 to its neutral position through the intermediary of the follow-up gear 16 as before. The lower diaphragm 36 is not exposed to air pressure but makes provision for self-alignment of the piston valve. It is necessary for the piston valve to respond to very small pressure differences, and therefore any side thrust on the valve must be avoided.

The fitting 22 on the lower end of the piston rod 21 is connected to the throttle valve 61 by a rod 62 (see Figure 3), so that the throttle valve will take up a position determined by the position of the piston and therefore corresponding to the setting of the distant pilot's throttle lever. The apparatus is shown in the drawings with the piston 11 in its lowermost position which corresponds to idling of the engine. Should the oil pressure be cut off under these conditions, the piston 11 will be automatically raised by a double spring 23, in the manner described below, thereby moving the throttle valve into an open position suitable for starting.

The swinging lever 13 is formed with a bulge 24, having a central slot through which passes a rod 25, carrying near its lower end a collar 26, and at its upper end a cap 27 forming an abutment for the upper end of the spring 23. Across the slot in the bulge 24 extends a slotted pin 28 having a flat on its lower surface which abuts against the top of the collar 26, the rod 25 passing through the slot in the pin 28. When therefore the piston 11 occupies a position near the lower end of the cylinder, the rod 25 is pulled down by the pin 28, thus compressing the spring 23 which is insufficiently powerful to oppose the pressure of the oil. On release of the oil pressure however, the spring 23 will expand and raise the piston 11 into a position corresponding to an open throttle. Owing to the lost motion connec-

tion between the rod 25 and the swinging lever 13, the spring 23 will not be compressed when the piston 11 is at the top of the cylinder, but should the pressure of the oil be cut off in this position the throttle will of course be sufficiently open to permit of starting of the engine.

What I claim as my invention and desire to secure by Letters Patent is:

1. In a remote acting fluid-pressure-operated throttle control system for an internal combustion engine, of the kind comprising a pressure-sensitive device located in the vicinity of the throttle valve and responsive to changes in fluid pressure transmitted to said device from a distance under the control of a distant throttle-actuating member, a relay valve operatively connected to the pressure-sensitive device, and a servomotor coupled to the throttle valve and operating under the control of the relay valve to take up a position determined by the fluid pressure acting on the pressure-sensitive device, the combination with the piston of the servomotor of a biasing device, arranged to be overridden by the fluid pressure in the servomotor on movement of the piston into a position corresponding to idling of the engine but operative to move the piston into an open throttle position suitable for starting in the event of failure of the fluid pressure in the servomotor, and a lost motion connection between the biasing device and the piston which operates to relieve the biasing device from stress except when the piston approaches the idling position.

2. In a remote acting fluid-pressure-operated throttle control system for an internal combustion engine, of the kind comprising a pressure-sensitive device located in the vicinity of the throttle valve and responsive to changes in fluid pressure transmitted to said device from a distance under the control of a distant throttle-actuating member, a relay valve operatively connected to the pressure-sensitive device, a servomotor operated by liquid pressure created by operation of the engine, said motor being coupled to the throttle valve and operating under the control of the relay valve to take up a position determined by the fluid pressure acting on the pressure-sensitive device, a link operatively interposed between the relay valve and servomotor, and a casing housing the relay valve and motor, the combination with the piston of the servomotor of a biasing device carried by the casing and operatively connected to said link and servomotor, arranged to be overridden by the fluid pressure in the servomotor on movement of the piston into a position corresponding to idling of the engine but operative to move the piston into an open throttle position suitable for starting.

EDWARD DODSON.
